UNITED STATES PATENT OFFICE.

WILLIAM L. BARNARD, OF ST. LOUIS, MISSOURI.

INCANDESCENT ELECTRIC LAMP.

1,273,130.

Specification of Letters Patent.

Patented July 23, 1918.

Application filed January 29, 1917. Serial No. 145,173.

To all whom it may concern:

Be it known that I, WILLIAM L. BARNARD, a citizen of the United States, and resident of St. Louis, Missouri, have invented certain new and useful Improvements in Incandescent Electric Lamps, of which the following is a specification containing a full, clear, and exact description, reference being had to the accompanying drawings, forming a part 10 hereof.

My invention relates to improvements in incandescent electric lamps, wherein a number of filaments in a single lamp or source of light are associated with a rotary switch in 15 a manner to produce continuous uniform luminosity as to the group of filaments, but intermittent luminosity as to the individual filaments whereby luminosity in a single source of light is attained without the usual 20 attendant heat radiation.

My object is to construct an incandescent electric lamp, having a number of filaments which are individually connected with a switch in a manner to energize a certain filament while the remaining filaments are radiating heat following their energization whereby to obtain a relatively increased candle power with a lesser current consumption and with no appreciable heat radiation, from 30 the lamp as a whole.

In the following specification I will fully, clearly and concisely set forth my improvements, definitely point out the same in my claim and illustrate one embodiment thereof in my drawings, in which—

Figure 1 is a sectional elevation of a lamp and switch constructed according to my invention.

Fig. 2 is a sectional plan of the lamp, 40 taken on the line 2—2 of Fig. 1, and

Fig. 3 is a diagram showing the wiring relating the filaments to the switch.

Referring to the accompanying drawings by numerals, I employ the numeral 5 to designate the bulb which is made of transparent material, preferably glass, and has integrally formed therewith and extended thereinto a single element consisting of a neck 6, a head 7 and a stem 8. The stem 8 has extended therethrough and projecting beyond its inner end a conductor 9 which has connected therewith both mechanically and electrically, a spider 10 and connected with each arm of the spider there is a filament 11.

55 The head 7 is provided with nipples corresponding in number and disposition with

the arms of the spider and extended through the neck 6 through the head 7 and through the nipples are the conductors 12, each of which connects with a filament 11. The 60 bulb is of the type which is hermetically sealed and a vacuum formed therein as is common, and by preference is arranged to be secured in a fixture comprising a socket 13, and further by preference the conductor 9 65 is electrically connected with the socket and the socket connected by means of a wire 14 with a source of electrical energy not shown. Each of the wires 12 extends to a contact 15 which contacts are made a part of a 70 rotary switch provided with a rotating brush 16, connected electrically with a source of energy by a wire 17, and which brush is mounted upon a shaft 18 having a pulley 19 connected therewith and arranged to be ro- 75 tated by any suitable means.

As shown in Figs. 1 and 2 the filaments 11 are grouped in circular arrangement, and as clearly shown in Fig. 3 the filaments bear such electrical relation with the contacts 15 as to cause energization and luminosity; first, of the filament 11 designated "A" in Fig. 2; then the filament "B" diametrically opposite the filament "A"; then the filament "C" and then "D", thereby 85 causing the lamp to shed a light of uniform intensity in all directions.

In my drawings I show a lamp in which there are fourteen of the filaments, but obviously any number of filaments may be employed without departing from the spirit 90 of my invention. The practical operation of the lamp is substantially as follows:

With energy flowing over the wire 17 through the shaft 18 of the rotary switch, 95 and the arm 16 thereof to one of the contacts 15 through the corresponding conductor 12 to a filament 11, through the spider 10, through the wire 9 to the socket 13 and thence through the wire 14 to the 100 source, and assuming the shaft 18 to be rotated it will be obvious that the duration of the energization and luminosity of the filaments is for a period of time, the brush 16 is in engagement with a contact and it 105 is to be understood that the speed of rotation of the brush is such as to energize a filament to the extent of luminosity and then immediately break the circuit.

This same filament of the group is then 110 permitted to remain unenergized until all of the remaining filaments of the group

have been energized, during which time, of course, the said filament while unenergized continues to be luminous, but with gradually decreasing intensity practically to the 5 time of its second or succeeding energization.

By this then, it will be understood that when the filament "A" is in circuit, it will have a maximum intensity of luminosity 10 for a period of time during the movement of the brush over its contact. The next succeeding contact is then engaged by the brush to energize the filament "B" which is diametrically opposite the filament "A". The 15 next succeeding contact is then engaged by the brush to energize the filament "C" which is separated from filaments A and B by an angle of ninety degrees and the next succeeding contact is then engaged by the brush 20 to energize the filament "D" which is diametrically opposite the filament "C", the remaining contacts being the same relative arrangement with each other in order to produce luminosity of uniform intensity in all 25 directions from the lamp.

By reason of the number of filaments and the relatively short interval between the energizations of the filaments in the order just described, it will be apparent that the 30 flow of energy is inconstant, hence there

will be a saving in current consumption in proportion to the spacing of the contacts of the switch, and that the light rays will be uniformly radiated from the lamp as a whole.

35

Having thus described my invention what I claim as new therein, and desire to secure by Letters Patent is:—

In combination with a single source of light, having a number of devices for translating electrical energy into light, a switch mechanically disconnected from the source of light, and arranged for continuous movement, and having a contact for each translating device of the source of light, and a 40 circuit including said translating devices, said switch and a source of electrical energy whereby each translating device may be momentarily energized in its turn to produce light during which time the remaining 45 translating devices will be deenergized and cooled.

In testimony whereof I have signed my name to this specification in presence of two subscribing witnesses.

WILLIAM L. BARNARD.
